UNITED STATES PATENT OFFICE.

LOUIS J. HANHART, OF CINCINNATI, OHIO, ASSIGNOR TO J. A. FAY & EGAN COMPANY,
OF CINCINNATI, OHIO, A CORPORATION OF WEST VIRGINIA.

SAWMILL SET-WORKS.

1,024,775.

Specification of Letters Patent.

Patented Apr. 30, 1912.

Application filed September 25, 1909. Serial No. 519,591.

To all whom it may concern:

Be it known that I, LOUIS J. HANHART, a citizen of the United States, residing at Cincinnati, in the county of Hamilton and 5 State of Ohio, have invented certain new and useful Improvements in Sawmill Set-Works, of which the following is a specification.

My invention relates to sawmill set-works, 10 and has for its object the provision of novel and improved means whereby setting of the knees is accomplished accurately and the distances of advance of the knees controlled in major steps capable of subdivision into minor 15 steps in novel manner for permitting accurate control of the distances of approach of the knees toward the saw-blade.

The invention will be readily understood from the following description and claims, 20 and from the drawings, in which latter:

Figure 1 is a side elevation of my invention, shown in connection with so much of a sawmill as is necessary to illustrate its application. Fig. 2 is a plan view of the same. 25 Fig. 3 is an enlarged side elevation of the operating lever, partly broken away, and showing the means for controlling its limits of movements; and, Fig. 4 is a longitudinal section of the same on the line $z-z$ of Fig. 3. 30 1 represents a sawmill carriage which is operable lengthwise, as on tracks 2, back and forth across the position of the saw-blade indicated at 3. The carriage has thereon suitable setting-knees 4 which are 35 movable crosswise of the carriage, a suitable number of setting-knees being employed. The setting-knees are instanced as stock or log-securing parts which have movement toward and from the saw-blade position.

40 The setting-knees may be slidable on head-blocks 5 and operated by a set-shaft 6 which has suitable connection with the setting-knees for moving the same toward the saw-blade position. Thus each setting-knee has 45 a rack 7 with which a pinion 8 on the set-shaft meshes, the setting-knees sliding on a guide-way 9 on the head-block. The setting-knees may be returned to initial position in a suitable manner, as by a spring 10 50 in a usual manner.

For moving the setting-knees toward the saw-blade position I provide an operating lever 11 which has suitable connection with the set-shaft 6. This connection between the 55 operating lever and the set-shaft may com-

prise a shaft 12 and pinions 13 14, shown as segment-pinions, rockable about the shaft 12, one of the pinions having a bracket 15 on its hub into which the operating lever is received. The pinions are suitably secured together for moving in unison, as by providing one of the pinions with a lug 16 and the other of the pinions with lugs 17 18, set-screws 19 20 being received in the lugs 17 18 for impinging against the lug 16 and thereby permitting adjustment between the segment-pinions 13 14 about their rotary axes and causing said pinions to move in unison. 60 65

21 22 are gears, shown as segment-gears, 70 journaled about the set-shaft 6. The segment-pinion 13 meshes with the segment-gear 21. The segment-pinion 14 meshes with a gear 23 mounted on a shaft 24 and in turn meshing with the segment-gear 22. 75 These parts may be mounted in side-frames 25 26 having bearings 27 for the set-shaft, bearings 28 for the shaft 12, and bearings 29 for the shaft 24.

31 is a ratchet-wheel secured to the set-shaft, with which suitable pawls on the segment-gears are arranged to make engagement. Thus the segment-gear 22 may carry pawls 32 33 on studs 34 35. In the construction shown one of the pawls engages 80 the teeth of the ratchet-wheel while the other is in mid-position, suitable means being provided for throwing the pawls out of engagement with the ratchet-wheel. Thus the pawl 32 is provided with a heel 36 85 90 adapted to engage a heel 37 on the pawl 33.

38 is a cam having a flat face 39 for permitting the pawls to engage the ratchet-wheel and provided with a handle 40 for causing the cam-face thereof to engage the 95 heel 36, thereby depressing both heels and disengaging both pawls. A spring 41 located between the heel 36 and the pawl 33 urges the pawls into engagement with the teeth of the ratchet-wheel. The segment-gear 22 is provided with similar pawls and attendant parts indicated by similar but primed reference numerals. 100

For controlling the movements of the setting-knees I provide a stop with relation 105 to which the operating lever has movement, the stop being adjustable for major divisions of angular movement of the operating lever, and a further stop provided with adjustable engaging faces for subdividing said 110

major divisions of angular movement of the operating lever into minor divisions thereof. Thus 46 is a bracket on one of the side-frames and has an arc-piece 47 thereon provided with a series of apertures 48 spaced apart at equidistant angles with relation to the pivot of the operating lever, which operates adjacent to said arc. A pin 49 is selectively received into said apertures and 5 forms a stop for the throw of the operating lever. A main stop for controlling the major divisions of travel of said operating lever and of travel of the setting-knees is thus provided. For subdividing these 10 major divisions of travel, I provide a supplemental stop shown as a block on said operating lever adjustable for presenting different points thereof to said stop. Thus 51 is a block which is provided with a series of 15 engaging faces or points of which there may be a suitable number, exemplified at 52^a 52^b 52^c 52^d. The block is adjustable on the lever for presenting any of said engaging points or faces to the main stop 49. 20 Thus the block has a guideway 53 therein through which the operating lever is received for permitting the block to be moved lengthwise of the operating lever. For positioning the block at suitable points length- 25 wise of the operating lever, in positions for selectively bringing the engaging faces, which may be stepped, into obstructing range of the stop 49, I provide obstructing parts between the operating lever and block. 30 Thus 54 is a tooth arranged to selectively engage notches 55 in the operating lever. The tooth 54 is shown on a lever 56 pivoted to the block at 57 and having a handle 58 adjacent to the handle 59 for moving the 35 block, a spring 60 between said levers urging the tooth into engagement with the notches, and the handles being relatively so disposed that the hand in grasping the operating handle 59, will also encompass the 40 handle 58.

61 is a permanent stop for the backward throw of the lever. It is preferably adjustable to take up wear of the parts. It is shown as a slide having an engaging face 50 62 thereon and adjustable on a lug 63 of the arc-piece by means of a bolt 64 threaded in a lug 65 of the slide and impinging the lug 63, a clamp-bolt 66 being received through a slot 67 in the slide into said lug 55 63, for clamping the permanent stop in adjusted position.

In operation, if it is desired to adjust the 60 range of movement of the operating lever for major divisions of angular movement thereof, the main stop or pin 49 is selectively placed into one of the apertures 48 and the block 51 adjusted into normal position on the operating lever for causing for instance the face 52^a thereof to engage the main stop 65 or pin. Each of these major divisions may

be the equivalent of a resultant travel in the setting-knees for instance of one-fourth inch. These major divisions may be subdivided into suitable minor divisions by the provision of the movable engaging faces on 70 the operating lever which may be brought into selective engagement with the pin 49 by adjustment of the block 51 on the operating lever. Each of these minor divisions of angular movement of the lever may be instanced as resulting in steps of one thirty-second inch of movement in the knees. These divisions may be varied and the resulting step-by-step movements of the knees may be subdivided into minute subdivisions 80 if desired.

By means of my improved device I am enabled to provide delicate and accurate adjustments of angular throw of the operating lever and resultant travel of the setting-knees, enabling me to provide small differences in the step-by-step travel of the setting-knees by mechanism which is simple and economical in construction and accurate 90 in results.

Having thus fully described my invention, what I claim as new and desire to secure by Letters Patent is:

1. In a manually operated sawmill set-works, the combination of a setting-knee, an 95 operating lever having operative connection with said setting-knee for setting the same, an adjustable permanent stop, a major-division stop, said operating lever having angular movement between said stops, means 100 for adjusting said major-division stop for major divisions of movement of said setting-knee, a contact-block mounted on and moving with said operating lever, said contact-block having contact-points thereon for minor divisions of movement of said setting-knee at one side of said contact-block co-operating with said major-division stop, and means for adjusting said block on said lever for placing selective ones of said contact-points into contacting range with said major-division stop for controlling minor divisions of movement of said setting-knee, and said contact-block having a contact-face at its opposite side contacting said permanent stop at similar lever positions throughout the range of adjustments of said contact-block.

2. In a manually operated sawmill set-works, the combination of a setting-knee, an 120 operating lever having operative connection with said setting-knee for setting the same, a stop for major divisions of movement of said setting-knee, means for adjusting said stop for said major divisions, a block, said block and operating lever having a guide-way therebetween extending lengthwise of said lever and movable with said lever, said guide-way comprising a guide-face movable into various angular distances with relation 125 130

to said stop, said block provided with contact-faces, and means for adjusting said block on said guide-face and lever for placing said contact-faces on said block selectively in range with said stop for minor adjustments of movement of said setting-knee, and the said guide-way arranged for receiving the blow of contact of said block with said stop in a direction substantially perpendicular to said guide-face.

3. In a manually operated sawmill set-works, the combination of a setting-knee, an operating lever having operative connection with said setting-knee for setting the same, a stop for major divisions of movement of said setting-knee, means for adjusting said stop for said major divisions, a block, said block and operating lever having a guide-way therebetween extending lengthwise of said lever and movable with said lever, said guide-way comprising a guide-face movable into various angular distances from said stop, said block provided with superposed contact-faces, and means for adjusting said block lengthwise of and on said operating lever for placing said contact-faces on said block selectively in range with said stop for minor divisions of movement of said setting-knee.

20 4. In a manually operated sawmill set-works, the combination of a setting-knee, an

operating lever having operative connection with said setting-knee for setting the same, a stop for major divisions of movement of said setting-knee, means for adjusting said stop for said major divisions, a block, said block and operating lever having a guide-way therebetween extending lengthwise of said lever and movable with said lever, said guide-way comprising a guide-face movable into various angular distances with relation to said stop, said block provided with superposed stepped contact-faces, said contact-faces being located in the angle between said stop and guide-face, and means for adjusting said block lengthwise of and on said operating lever for placing said stepped contact-faces on said block selectively in range with said stop for minor divisions of movement of said setting-knee, and the said 50 guide-face arranged for receiving the blow of contact of said block with said stop in a direction substantially perpendicular to said guide-face.

In testimony whereof, I have signed my name hereto in the presence of two subscribing witnesses.

LOUIS J. HANHART.
